Primary Examiner — Samantha Q Lawrence(74) *Attorney, Agent, or Firm* — Seager, Tufte & Wickhem LLP(57) **CLAIM**

The ornamental design of a soft tissue cutting device, as shown and described.

DESCRIPTION

FIG. 1 is a top perspective view of a soft tissue cutting device.

FIG. 2 is a bottom perspective view of the soft tissue cutting device of FIG. 1.

FIG. 3 is a rear view of the soft tissue cutting device of FIG. 1.

FIG. 4 is a front view of the soft tissue cutting device of FIG. 1.

FIG. 5 is a left side view of the soft tissue cutting device of FIG. 1.

FIG. 6 is a right side view of the soft tissue cutting device of FIG. 1.

FIG. 7 is a top view of the soft tissue cutting device of FIG. 1; and,

FIG. 8 is a bottom view of the soft tissue cutting device of FIG. 1.

The broken lines shown in FIGS. 1-8 illustrate portions of the soft tissue cutting device that form no part of the claimed design.
